UNITED STATES PATENT OFFICE.

OSCAR LOEWENBACH, OF MILWAUKEE, WISCONSIN.

DETACHABLE COVER FOR PADS, BOOKS, ETC.

1,415,591.

Specification of Letters Patent.

Patented May 9, 1922.

Application filed April 5, 1920. Serial No. 371,389.

To all whom it may concern:

Be it known that I, OSCAR LOEWENBACH, a citizen of the United States, and resident of Milwaukee, in the county of Milwaukee and State of Wisconsin, have invented certain new and useful Improvements in Detachable Covers for Pads, Books, etc.; and I do hereby declare that the following is a full, clear, and exact description thereof.

10 My invention pertains to new and useful improvements in detachable covers for pads, notebooks and the like, and has particular reference to means for securing fillers in suitable covers.

15 In the present methods of detachably securing filler binders within a pair of covers, the securing means sooner or later becomes badly worn and useless and as this means is largely secured to the covers, the same 20 must be discarded as useless. As such covers are more or less expensive, the cost of replacement is considerable.

25 Therefore the principal object of the invention is to provide an improved binder for fillers and the like which is so associated with a suitable form of cover as to entirely eliminate the difficulties heretofore experienced. If the binder forming part of my invention becomes worn and useless, it may 30 be readily replaced at a slight cost.

35 With this general object in view the invention consists in the novel features of construction, combination and arrangement of parts which will be hereinafter more particularly described and claimed.

In the accompanying drawing:

Figure 1 represents a perspective view of a detachable notebook cover constructed in accordance with the invention.

40 Figure 2 is a similar view of a binder used in connection with the cover shown in Figure 1, these two parts forming the improved structure.

45 Figure 3 is a sectional view through the invention showing the association of a filler therewith.

50 Referring more particularly to the accompanying drawing, the reference character 1 denotes a top cover member of a notebook cover which has a bottom cover member 2 connected therewith by means of a flexible back 3. These several parts of the notebook cover may be constructed of any desirable material and in any preferred size, 55 depending entirely upon the use to which it is put. In any instance, however, the

lower cover member 2 adjacent this connection with the flexible back 3 is provided with a pair of upstanding posts 4. In other words these posts extend transversely of the 60 cover and from the lower cover member 2 to a point adjacent the upper cover member 1, and their free ends are provided with socket engaging heads 5. Any preferred means may be employed for securing these 65 posts to the lower cover member.

The binder 6, which is shown in detail in Figure 2 includes a pair of substantially rectangular elongated plates which may be termed a lower binder plate 7 and an upper 70 plate 8, and a flexible back portion 9 connecting the same. The lower plate 7 is provided with a pair of spaced eyelets 10, the distance between the same being equal to that between the posts 4 on which they 75 are designed to slide. The other or upper plate 8, on the other hand, has a pair of spaced sockets 11 which, when the binder is in use are alined with the eyelets 10 and consequently are engageable with the heads 5 80 of the posts 4.

When in use a filler 12 is disposed between the plates 7 and 8 of the binder and has openings therein receiving the posts 4. In assembling the filler 12 with parts of the 85 invention, the top cover member 1 is turned back to open the notebook cover and expose the posts 4, whereupon the latter may have the eyelets 10 of the plate 7 slid thereover. With the binder laid open in the same manner as the cover member 1, the filler 12 may be disposed on the plate 7 and the lower cover member 2, whereupon the upper plate of the binder may be turned forward to engage the sockets 11 with the heads 5 of the posts, 95 and when said sockets frictionally snap over said heads, the binder is retained in the position shown in Figure 3.

This holds the filler and the several leaves thereof within the cover and permits the 100 top cover member 1 to be opened or closed together with or independently of said leaves.

From the foregoing description taken in connection with the accompanying drawing 105 it will be seen that in view of the fact that the only attaching members carried by the cover are the posts 4, and owing to the manner of attaching the same and the nature of their construction, they will last 110 practically indefinitely, and the cover will have a relatively long life. Even should

the posts become worn or broken, others may be readily substituted therefor. Various changes may be made in the form and proportions of the different parts of the invention without departing from or sacrificing any of the principles or the advantages thereof.

I claim:

The combination with a pair of cover members hingedly connected together, of a pair of posts carried by one of the cover members and extending toward the other

member, a binder having corresponding portions to engage the opposite sides of a filler, eyelets in one of said portions and slidables 15 on the posts and attaching sockets on the other of said portions for cooperation with the free ends of said posts.

In testimony that I claim the foregoing I have hereunto set my hand at Milwauke, in the county of Milwaukee and State of Wisconsin.

OSCAR LOEWENBACH.
